UNITED STATES PATENT OFFICE

THOMAS H. HURST, OF WICHITA, KANSAS

COMBINATION PLIERS AND TOOL

Application filed February 1, 1928. Serial No. 251,082.

The invention relates to a combination plier and tool in which the pliers themselves have various characteristics common to pliers and are provided with suitable fittings and accessories which in combination produce varied 5 series which in combination produce varied other tool elements, such for instance, a screw driver, a wrench, a hammer and the like.

In the drawings; Fig. 1 represents a side view of the tool. Fig. 2 is an edge view of 10 Fig. 1. Fig. 3 is a sectional view taken along the line III—III in Fig. 1. Fig. 4 is a perspective view of a socket element, which is adapted to be fitted over the pliers when it is desired to use the pliers as a handle for a 15 socket wrench. Fig. 5 is a perspective view of a hammer head adapted to also fit over the pliers and whereby the pliers become the handle of the composite hammer. Fig. 6 is a 20 socket carrying a screw driver element, with parts in section to disclose operative connecting means. Fig. 7 is a side view of Fig. 6. Similar numerals of reference indicate corresponding parts throughout all the figures 25 of the drawings.

Referring to the drawings, the pliers include a pair of members pivotally connected by the bolt 10; one element includes a handle 11 and jaw portion 12, while the other element has a handle 13 and jaw portion 14.

At 15 are seen the knives 15^x and 15^y serving as wire cutting means. The jaws are fashioned as at 16 and 16^x with teeth elements on cutaway portions which when clamped as at 30 16^y present a square toothed socket which may be employed as desired or used as a pipe wrench. Outwardly projecting pins 17 and 18 are seen upon the outer walls for the jaws 14 and 12 respectively. The jaws 12 and 14

40 converge as in Fig. 1 or so that the socket seen in Fig. 4 may be slipped down upon the jaws of the pliers, then the handles would be separated as seen in Fig. 6 or so that the pins 17 and 18 would be permitted to engage within 45 holes such as 19 in the sides of the socket and the jaws then have their opposite side faces set parallel to each other or so as to snugly fit against the sides 20 and 21 of the box-like socket element as seen in Fig. 4 or 50 20^x and 21^x of the screw driver socket element

seen in Fig. 6. It is obvious that the socket cannot be removed until the jaws are closed as in Fig. 1. This provides a rigid composite tool for the purpose desired.

Hinged at 22 is seen a strut arm 23 carried by a boss 24 near the base of the handle 13. This strut arm is provided with a ball 25 pressed outwardly by a spring 26 recessed within a hole 27 properly formed in the end of the arm 23 as illustrated. At 28 is a stop on the handle 13 with which the ball 25 makes a friction contact at 29 when positioned as in Fig. 1. In Fig. 6 the arm has been pivoted to the position 30 against the arm 11 to maintain the pressure of the jaws 12—14 to hold the pins 17—18 to their proper relationship with the holes 19 of the socket element. A further object of the arm 23 in the position seen in Fig. 6 is to increase the strength of the composite handle 11—13 when used as a wrench. The socket seen in Fig. 4 is provided with a hexagonal pin 31 having a spring pressure ball 32 adapted to receive a socket wrench and to hold the same against falling off. The hammer head seen in Fig. 5 is of 75 socket formation adapted to receive the jaws 12 and 14, the slots 33 and 34 serving to admit the pins 17 and 18.

Such modifications may be employed as lie within the scope of the appended claims.

Having fully described my invention what I now claim as new and desire to secure by Letters Patent is:

1. In a combination tool, a pair of pliers, the jaws of which each carry a pin element; a socket provided with tool means, formed to receive the jaws and the pins, and a strut arm hinged to one of the handles of said pliers; said arm having a spring actuated ball operatively positioned within the said arm; and a stop on the said handle for contacting said spring actuated ball.

2. In a combination tool, a pair of pliers and a socket element; the jaws of said pliers having projecting pins and in their closed position contracting to loosely enter within said socket; and openings within said socket walls for receiving the projecting pin elements of said jaws and means for then spreading the handles of said pliers and for locking 100

- said handles in such spread position, said means including a strut arm hinged to one handle thereof; said arm having a spring actuated ball operatively positioned within the said arm, and a stop on said handle for normally holding said strut arm against said handle for effecting release of the socket element when locked on the plier jaws, said spring actuated ball means likewise permitting release of said hinged strut arm to bear against the opposite handle element, or so as to rigidly attach said socket to said plier jaws.
- 10 3. A pair of pliers, a strut arm hinged to one handle thereof; said arm having a spring actuated ball operatively positioned within the said arm, and a stop on the handle for contacting said spring actuated ball.
- 15

In testimony whereof I affix my signature.

THOMAS H. HURST.
